FOREIGN PATENT DOCUMENTS

CA 219035 * 6/2024

Primary Examiner — Kimberly Barnes*(74) Attorney, Agent, or Firm* — Muetting Raasch Group**(57) CLAIM**

The ornamental design for an anti-wrinkle appliance as shown and described.

DESCRIPTION

FIG. 1 is a back left perspective view of an anti-wrinkle appliance showing our new design;

FIG. 2 is a back right perspective view thereof;

FIG. 3 is a bottom view thereof;

FIG. 4 is a top view thereof;

FIG. 5 is a right view thereof;

FIG. 6 is a right perspective view thereof;

FIG. 7 is a left perspective view thereof;

FIG. 8 is a left view thereof;

FIG. 9 is a bottom back perspective view thereof;

FIG. 10 is a front view thereof; and,

FIG. 11 is a back view thereof.
